MUSICAL INSTRUMENT

Ebenezer Emmet Reid, Baltimore, Md.

Application May 25, 1937, Serial No. 144,671

12 Claims. (Cl. 84—1.17)

My invention relates to musical instruments and the like. Important advantages that can be realized in practice through the invention include flexibility or operation; wide range of pitch and volume, covering as many octaves as desired; perfection and variety of tone quality, equalling or exceeding what is possible on the best organs; and ability to play in either the equitempered or the natural harmonic scale, with full variety of notes in all octaves. Without excessive complication, an instrument embodying my invention (as hereinafter described) can be changed at will from the equitempered scale intonation to a natural harmonic scale intonation,—or any other desired scale of intonation,—and vice versa; and in the harmonic scale, it can be adapted at will to music written in any key(s). The shift of scale or key of musical intonation can be made by the player in a moment, and can be repeated as often as desired during the playing of a composition.

The changing of scale or key of musical intonation according to my invention is readily applicable to any type of instrument in which the pitch of the musical notes or tones depends on the rate or speed of motion of controlling parts, and may be effected by changing the relative speeds of various pitch-controlling rotors. One way of doing this is to change the ratios of gear combinations by which the various rotors are driven from one or more common drive-shafts. As the corresponding notes in all octaves covered by an instrument can be produced by one rotary unit, and as only twelve such rotary units are generally needed in a complete instrument, the mechanism for effecting the change-over may be comparatively simple. I have hereinbefore explained these and other features of my invention in connection with an electrical type of instrument in which rotating devices cooperate in the generation of electrical impulses which are converted into sounds. But it will be understood that this is only illustrative, so far as the broader features and principles of the invention are concerned.

One way of producing electrical impulses of suitable nature and frequency for musical purposes is to vary a magnetic flux affecting a conductor, such as a coil or winding, at a frequency corresponding to the frequency of sound vibrations of the pitch desired, thus producing an alternating electric current in the conductor.

The frequencies useful in music are those from about 25 to about 6000 or more per second. Very

weak currents can be amplified (by means well known in radio) to actuate a diaphragm (such as used in a telephone, or in a radio or other dynamic loud-speaker), thus producing sounds of corresponding character. A way of producing flux changes in a coil or winding is to vary the permeability in a magnetic field affecting it, as by vibrating or otherwise moving a ferromagnet device or member in or through the field with suitable frequency. A rotor embodying one or more (soft) ferrous metal (iron or steel) members answers this purpose very well; and a disc or other rotor with an end face presenting a series of such members forming a "track" of varied permeability affords special advantages. The permeability-varying device or series of members may be conveniently referred to as a "tone track." While the field for the generating coil may be produced by a permanent magnet, I at present generally prefer to produce it electrically, by passing (direct) current through an exciting "primary" coil or winding associated with the generating coil as secondary. By controlling and varying the exciting current in the primary coil, the intensity of the resulting musical tone from the sound device (loud-speaker, etc.) can be controlled and varied, and several important results thereby secured. However, like results can be obtained by the well-known means of volume-control employed in radio, which may be used either in lieu of excitation control, or concurrently therewith.

The tones or notes of the organ and of other musical instruments are complex, including "harmonic" vibrations of frequencies higher than the dominant or fundamental ones, and also (sometimes) a lower frequency vibration, which gives dignity to the tone. It is by the number, relative intensity, and other interrelations of these component partials that the tonal characters of different instruments are determined. In the tones produced by pipes and strings, it is found that if the frequency of the fundamental or "first partial" is n , those of the higher partials of "overtones" will be $2n, 3n, 4n, 5n, 6n, 7n, 8n$, etc.—up to a total of eight to twelve partials, or even more. It is therefore necessary to generate electrical impulses of corresponding frequencies, and to transmit them to the sound device in suitable relative intensities. I generally prefer to proportion the intensities of the partials of a note in generating the corresponding electrical impulses, by suitably regulating the exciting or activating currents in the various primary coils,

as above mentioned. By such regulation, the characteristic tones of almost any ordinary musical instrument can be simulated on one and the same electrical instrument just as desired,—such as organ diapason, violin, oboe, etc. Alternatively, and with like variety of effects, the relative intensities of the electrical impulses for the various partials may be suitably changed in transmitting them to the sound device, by well-known means of volume-control such as employed in radio. If desired, these modes of proportioning the partials may be used together.

While a single loud-speaker or sound device may suffice, it is often advantageous to employ a number of such devices, suitably connected to the electrical output circuit of an instrument. In a large auditorium, or for out-of-doors concerts or the like, a multiplicity of sound devices will often be needed to produce sufficient volume of sound without forcing. Also, an extra sound device may sometimes be installed in a distant gallery or cupola, to give "echo organ" effects, with arrangements for throwing this or the main sound device into or out of action, so that they shall be heard alternately,—or even both together sometimes. In fine instruments, it may be preferred to use several different sound devices, differently constructed or adjusted, for tones of different pitch or quality, so as to produce all tones as correctly and agreeably as possible: e. g., one sound device for low notes, and another for high notes; or one for low tones, another for intermediate tones, and yet another for high tones.

The partials of any one note or tone may be produced all from the same tone-track, or from several tone-tracks, or each from a separate tone-track. In employing rotors with end-faces or disc-elements presenting tone tracks of varied permeability, I prefer to provide tracks for all the partials of a tone or note on the end-face(s) of a single rotor. Indeed, I may even provide for two notes an octave apart on the opposite faces of the same disc or rotor. Whatever the type of rotor structure, I prefer to combine in one rotary unit the permeability-varying devices necessary for corresponding notes (including all their partials) in all the octaves covered by an instrument. This not only insures that these notes shall always have the correct relations to one another, but also simplifies the change-over between the equitempered and the harmonic scales, or from playing in one key to playing in another, as mentioned above.

The rotors of my instrument may be driven by any convenient (electric) motor(s), such as a constant speed type of A. C. motor supplied from an A. C. lighting or power circuit with constant-frequency regulation. For exciting the magnetic fields of electrical impulse generators, (direct) current may be taken from any suitable source, with constant voltage regulation, such as a battery of dry cells, a storage battery, a D. C. lighting or power circuit, or a motor-generator set operated from any suitable A. C. circuit.

Various features and advantages of the invention besides those already referred to will become apparent from the following description of species or forms of embodiment, and from the drawings. All the features shown and described are, indeed, of my invention, so far as novel over the prior art.

In the drawings, Fig. 1 is an elementary diagram of one electrical type of musical instrument embodying my invention.

Fig. 2 is a perspective or tilted view (partly diagrammatic) of a generator of electrical impulses suitable for use in the instrument of Fig. 1, including a disc type of rotor and a coacting generator device, and provided with means for intensifying the generating action,—the rotor disc being shown partly broken away and in section.

Fig. 3 is a similar view of a rotor of somewhat different form and construction, with a plurality of associated generator devices.

Fig. 4 is a similar view illustrating yet another form of rotor and generator device.

Fig. 5 is a diagram illustrating the generation and synthesis of partials to produce a complex musical tone.

Fig. 6 is a perspective or tilted diagrammatic view of a disc rotor with a multiplicity of tone-tracks and generator devices, adaptable for producing the component partials of a complex tone or note, and for use in an instrument (like an organ) having a plurality of playing manuals or keyboards.

Fig. 7 is a diagrammatic side view of a generator device with a plurality of generating coils, as well as a plurality of exciting coils.

Fig. 8 is a general diagram of typical circuits and parts of a plural-manual instrument, including a plan view of a rotor and associated generator devices similar to those in Fig. 2, and showing certain parts in cross-section.

Fig. 9 is a general diagram affording an edge view of a number of rotor discs grouped together and interconnected as a rotary unit, including only some of the circuits for one manual, and showing certain parts wholly or partly in section.

Fig. 10 is a diagrammatic plan-like view illustrating the organization of an instrument adapted to be changed over for playing in different scales or different keys,—either an electrical instrument, or one of any other type in which musical pitch is controlled by speed of rotation,—some parts being shown in cross-section, and certain parts omitted for the sake of clearness.

Fig. 11 is a diagrammatic side and end view of parts of the mechanism at the extreme right of Figs. 10 and 12 in proper relation to one another, showing some parts that are omitted from Figs. 10 and 12, and omitting certain parts that are shown in Figs. 10 and 12.

Fig. 12 is a diagrammatic plan view of parts which are omitted from Fig. 10 because they overlie those there shown, but which appear in Fig. 11.

Fig. 13 is a view at right angles to Fig. 12, illustrating the action of an interlock in connection with the mechanism of Fig. 12.

Fig. 14 is a fragmentary diagrammatic view illustrating a coupler device different from those in Figs. 10 and 11, with associated parts of the mechanism.

Fig. 15 is a fragmentary view at right angles to Fig. 14.

Fig. 16 is a fragmentary view similar to Fig. 11, illustrating a variant arrangement for changing over from one scale or key to another.

Elementary general explanation

An electrical impulse generator is shown in Fig. 1 as including a device P for producing flux variations, and a coacting generating device Q comprising a generating coil or winding 15, with leads 16 connecting it to or across an output circuit 17, at points h, h. In or across the output circuit 17 is also connected a sound device S, such as a loud-speaker or a telephone receiver; and an am-

Various rotors and generator devices

plifier X (such as used in radio) may be interposed in the circuit between coil 15 and sound device S. While a magnetic field or flux affecting the generating coil 15 may be produced by a permanent magnet (core) associated with this coil or winding as part of the generator device Q, I prefer to produce the field flux electrically, by including in the generator device Q an exciting "field" coil or winding 20, in inductive relation as primary to the coil 15 as a secondary. The activating primary coil 20 is connected by leads 21 in or across a (direct current) power circuit 22, at points i, j. The coils 15, 20 may be wound on a common core 24, which is preferably of soft ferromagnetic (paramagnetic) material, as soft steel or iron. Though illustrated in Fig. 1 as a straight bar with a conically pointed active end, the core 24 may in practice have any preferred form. To produce flux variations affecting coils 15 and 20 by variations of the magnetic permeability in their field, a device, track, or series-of-members P affording such permeability variations may be associated with the generating device Q, with provision for relative movement of the devices P and Q. As here shown, the device P consists of a serrated or sinuous ferrous metal strip or wire 25 near one (pointed) pole end of core 24. A playing key K is shown in Fig. 1, which when operated (depressed) closes a normally open (and self-opening) switch 26, either in the total secondary circuit between coil 15 and sound device S, or in the total primary circuit between coil 20 and the source of exciting current,—or both. It is convenient to distinguish portions of these total circuits including the tone control switch(es) 26 as secondary and primary playing circuits 27, 28: as marked in Fig. 1, they are interposed between one lead 16 and a point of connection h to the output circuit 17, and between one lead 21 and a point of connection i to the power circuit 22. Circuit 27 may also be appropriately called a "tone circuit."

With switch(es) 26 closed and current flowing in the primary coil 20, relative movement of the regularly serrated or corrugated wire 25 and the generating device Q at uniform speed produces a series of electrical impulses (an alternating current) in the secondary coil 15, playing or tone circuit 27, and output circuit 17; and this current is amplified and converted into a musical tone or note by amplifier X and sound device S. I usually prefer to corrugate the wire 25 to such a shape that the alternating secondary current is truly sinusoidal and produces a pure tuning-fork tone in the sound device S; but other shapes may be used, especially in large instruments. It is generally more convenient to move the device P (the wire 25), rather than the generating device Q. The frequency of the secondary current and the pitch of the tone depend on the speed of movement of the wire 25 as it travels in varying proximity to the generating device Q, as well as on the pitch of the corrugation of the wire 25; while the intensity or loudness of the tone depends on these same factors and on the strength of the exciting primary current, and can be changed at will by changing this exciting current. The intensity or loudness of the tone can also be changed, of course, by changing the proportion in which the secondary current affects the sound device, S,—as by a variable resistance 29 shunted across the circuit anywhere between coil 15 and sound device S, or by a variable transformer 299 interposed in the circuit 17.

As already suggested, it is advantageous to revolve the permeability-varying device P adjacent the generating device Q, and to embody or present it at an end or lateral face of a rotor R (which is preferably of disc form), as a "track" extending around the axis of rotation. Using the corrugated wire 25 of Fig. 1 (or the like) for the device or track P of the rotor R, I prefer to mount this wire 25 at the face of a (non-magnetic) carrier disc-element, as by embedding the wire (wholly or partially) in a groove 30 concentric with the axis 31, Fig. 2. As here indicated,—and partly revealed by the partial cutting away 15 of the carrier margin,—the wire 25 is of rectangular (square) cross-section, is bent into a circle or hoop, and is also bent in corrugations or serrations at right angles to the general plane of the hoop and of the carrier face. The circumference of the hoop 25 is an exact multiple of the pitch of the corrugations, so that an exactly integral number of corrugations is included. Preferably, the hoop 25 is a continuous ring, without break or joint of such character as to 25 affect its permeability; or else any break or joint is located in a depressed bend, where its influence on the magnetic field of the device Q will be minimized. Using a carrier of suitably soft metal like brass, copper, or aluminum, the wire 30 25 may be secured in the annular groove 30 by slightly forcing in the sides of the groove, either all the way around, or at suitable intervals as indicated at 32.

The electrical impulses or alternating current 35 produced in secondary coil 15 by rotation of the soft ferromagnetic tone-track consisting of hoop 25 adjacent generator device Q may be considerably strengthened by inductively magnetizing the hoop adjacent the device Q to a polarity the reverse of that in said device Q due to its exciting primary coil 20. For this purpose, a magnet device or inductor 33 may be placed close adjacent the hoop 25 at a point directly (diametrically) opposite said device Q with respect to the axis 31. 45 This device 33 is shown as a magnet bar with one (conically pointed) end close to the hoop 25 as it revolves,—either a permanent magnet bar of steel, or a soft ferromagnetic bar inductively magnetized by a coil 34 wound around it, and 50 connectible to any suitable (direct current) circuit. Thus the polarity of hoop 25 adjacent the device Q is the reverse of that induced in said hoop adjacent the device 33. If the bar 33 is a permanent magnet, the coil 34 may be useful to 55 remagnetize it to proper strength occasionally.

The non-magnetic carrier of rotor R is shown in Fig. 2 as a flat disc of uniform (axial) thickness sufficient to embed and secure the corrugated wire 25, with reasonable strength of metal 60 at the bottom of the groove 30. The non-magnetic carrier "disc" of the rotor R shown in Fig. 3 is neither flat nor of uniform thickness, but conical-faced. Sometimes it may be desirable to make the carrier of double thickness, more or less,—in effect embodying two disc elements "back to back",—with a serrated ferromagnetic hoop 25 in each lateral or end face, and a corresponding generator device Q for each hoop. In this case, the thickness may be sufficient to obviate any objectionable "cross" influence of either hoop 25 on the generator device Q associated with the other hoop. But when the musical interrelations of the devices Q, Q render such "cross" influence unobjectionable, or when such 75

cross influence can be precluded by making the two hoops 25 of very different radii, the minimum thickness is merely that required for mechanical strength. Aside from considerations of space and cost, there is no maximum limit of thickness: i. e., one or two disc elements may be embodied in a carrier of any thickness or axial length whatever. Fig. 3 also illustrates a variation in the continuous serrated hoops 25, 25, 10 which do not consist of bent wire as in Figs. 1 and 2, but of flat strip metal, with straight edges at the groove bottoms and serrated or corrugated outer edges adjacent the devices Q, Q. As here shown, these hoops 25 are of different radii. 15 Fig. 3 also illustrates an additional and more powerful generator device Q associated with one of the serrated hoops 25. This device Q has its core 24 bent to a horseshoe or U-shape, with conically pointed ends spaced apart along the path 20 of travel of the ring 25 a distance equal to (an integral multiple of) the pitch of the hoop corrugations. Both the core ends being located close to the path of the crests of these corrugations, the magnetic circuit in the core 24 is completed through the hoop when the hoop crests are adjacent the core ends, and is broken when the hoop depressions are opposite the core ends. In other words, the ring 25 completes the magnetic circuit of the core 24 only periodically, as 25 different crests concurrently pass the core ends.

This great change in magnetic permeability produces correspondingly strong electrical impulses in the generating coil 15, shown on one arm of the core 24. The exciting or activating coil 20 is shown on the bend of the horseshoe core 24, where its effect is the greatest.

In the operation of the impulse or alternating current generators with straight core-bars 25 that are shown in Figs. 1, 2 and 3, it is mainly the 40 crest members or portions of the wire or hoop 25 moving close to the generator devices Q that produce changes of magnetic permeability and flux in the fields of the coils 15, resulting in electrical impulses in these coils. Hence the depressed 45 portions between the crest members might just about as well be omitted, so far as generation of the desired electrical impulses is concerned. Accordingly, Fig. 4 shows a permeability-varying circular tone-track P composed of a series of 50 equally spaced, separate, soft ferromagnetic members 35 forming inserts set into recesses or holes in the non-magnetic carrier disc of the rotor R. These members 35 correspond in number to the crest members or portions of the hoops 55 25 of Figs. 2 and 3 that would be used to produce the desired musical tone. As here shown, the inserts 35 are in effect round plugs fixed in holes that extend clear through the carrier disc, so that the members 35 are presented at both disc 60 faces. Also, the generator device Q is shown as different from those in Figs. 1, 2, 3. In Fig. 4, the soft ferromagnetic core bar 24 is bent into an elongated "chain-link" form somewhat resembling a large C, with the (conically pointed) 65 ends of its axially aligned limbs located at opposite sides of the carrier disc, and spaced to just let the plugs 35 pass between,—thus momentarily completing the magnetic circuit in the core 24. The generating and exciting coils 15, 20 are wound on one end and on the middle of this core-bar 24.

Complex tones from a single tone track

A simple way of generating and synthesizing component partials of a musical tone or note from a single tone track P is illustrated in Fig. 5.

For simplicity and clearness, this track P is shown merely as a corrugated or serrated strip or wire 25 lying (like that in Fig. 1) in the plane of the paper,—as if taken out of the rotor carrier groove 30 in Fig. 2 and flattened. This track P 5 may travel to the right, as indicated by the arrow.

For the first partial or fundamental of frequency n , the generator device Q is like that shown in Figs. 1 and 2, and its generating and exciting coils 15, 20 are connected by leads 16, 21 to secondary and primary playing circuits 27, 28. The generator device Q₂ for the second partial (or first overtone) of frequency $2n$ is shown as having two generating coils 15, 15 on core bars which in this particular instance are "limbs" of a unitary 15 forked core structure 24, whose single "body" carries a single exciting coil 20. The coils 15, 15 and 20 of this device Q₂ are also connected to the circuits 27, 28. As shown, the generator device Q is directly opposite a crest of the corrugated 20 wire 25; the first or left-hand limb (and coil 15) of the device Q₂ is directly opposite another such crest; and its second or right-hand limb (and coil 15) is directly opposite a depression of the corrugated wire. If then, a crest of the 25 moving wire 25 passes coil 15 of device Q every 1/n of a second, so as to produce electrical impulses of frequency n in tone circuit 27, such a crest will pass one or other of the coils 15, 15 of device Q₂ every 1/2n of a second, resulting in 30 electrical impulses in the circuit 27 at a frequency 2n, as required for the second partial.

For the third partial (or second overtone) of frequency $3n$, the generator device Q₃ is shown 35 as consisting of three devices Q like that in Figs. 1 and 2,—with their core bars 24 attached (like limbs) to a common (supporting) member 36 that may be of either soft ferromagnetic or non-magnetic material. The coils 15, 15, 15 and 20, 20, 20 are connected to the circuits 27 and 40 28,—though as here shown the coils 20, 20, 20 are in series with one another. The first or left-hand limb (and coil 15) of the device Q₃ is opposite a crest of the corrugated wire 25; the second limb (and coil 15) is 1/3 the pitch or interval 45 of the corrugations to the right of a crest; and the third limb (and coil 15) is 2/3 the corrugation pitch or interval to the right of a crest: hence electrical impulses of frequency $3n$ are produced in the tone circuit 27, as required for the 50 third partial. Stating the matter in general terms, it will be seen that the generating coils 15 of each overtone generator device Q₂, Q₃, etc. are spaced along the track P out of phase with 55 one another, with respect to its variations, by fractions of the corrugation pitch or interval corresponding to the number of this partial (2nd, 3rd, etc.)—or, more properly, to its multiple of the fundamental frequency n . Obviously, any 60 number of such generator devices can be provided, to produce any desired partials,—the only limit being that of convenient space afforded by the length of the track P.

As shown in Fig. 5, the first limbs of all the 65 devices Q, Q₂, Q₃ are preferably so located as to be opposite to crests of the corrugated wire 25 simultaneously, in order that the electrical impulses or alternating currents for all the partials n , $2n$, $3n$, etc., may be in phase with one another. 70 It will also be observed in Fig. 5 that while the limbs of device Q₂ are spaced apart only half the pitch of the corrugations of the wire 25, those of the device Q₃ are spaced a distance 1 1/3 this pitch. This extra wide spacing avoids crowding the 75

limbs together into the pitch of one corrugation, and may be especially desirable for the higher partials, of frequencies $4n$, $5n$, $6n$, $7n$, $8n$, $10n$, etc. In practice, of course, the track P may 5 preferably be embodied in a rotor R of any suitable type, such as those shown in Figs. 2, 3, 4, or even 6.

10 Rotores with plural tone-tracks; complex tones; plural manuals or pedals

Fig. 6 illustrates a rotor R with a plurality of tone-tracks P of varied permeability concentric with its axis of rotation 31. These tracks P may be of any suitable construction, several of 15 which have already been explained in connection with Figs. 2, 3, and 4. Such a rotor R can advantageously be used to produce all the partials for one tone or note of an instrument—or even for two corresponding notes of different octaves. 20 if the number of partials necessary to give a pleasing tone quality or timbre does not exceed the number of tracks P that can be satisfactorily accommodated at one side of a carrier disc of convenient size. The number of partials required for a good tone depends on both the character of the tone and its fundamental pitch. 25 Four or five partials generally suffice for a fair diapason tone; but eight or nine may be used to assure variety or richness of tone, or even more. 30 Violin tones require more partials than diapason tones of the same pitch. But in the higher notes of a keyboard of usual organ range, some two or three or four partials suffice: i. e., the highest note of such a keyboard has a fundamental frequency of 2093 vibrations per second, and its third partial (second overtone) has a frequency of 6279, which is about the limit of usefulness in music. The rotor R shown in Fig. 6 has six concentric tracks P with one or more generator devices Q for each, so as to produce a complete 40 tone, and may appropriately be distinguished as a "full-tone rotor."

In using the corrugated hoop or spaced plug 45 constructions of Figs. 2, 3, and 4 for a multi-track rotor R such as shown in Fig. 6, and employing one standard pitch or spacing for the corrugations or plugs of all the tracks P, the tracks P to produce the fundamental and higher partials of frequencies n , $2n$, $3n$, $4n$, etc. may have radii 50 r , $2r$, $3r$, $4r$, etc., and those for a sub-partial of frequency $\frac{1}{2}n$ may have the radius $\frac{1}{2}r$. However, it may sometimes be found convenient to 55 make the pitch or spacing of the corrugations or plugs greater for the lower partials of a full-tone-rotor than for the rest, or less for the higher partials, so as to avoid having to make the rotor R excessively large. Accordingly, no attempt 60 has been made in Fig. 6 to indicate the specific construction of the tracks P, or even to proportion the radii of these tracks on any consistent basis of corrugation pitch or plug spacing. But 65 an important point illustrated by Fig. 6 is that when the tracks P for all partials of a tone or note are on one rotor (or rotary unit) R, the frequencies of the partials will always be in the exact ratios fixed by the construction of these tracks, under all circumstances.

Another important advantage of a multi-track 70 rotor R as shown in Fig. 6 is the compactness of space in which many partials can be generated, as contrasted with forms of rotor in which tracks P for the component partials of the tones are presented peripherally, rather than endwise or laterally. This compactness of many tracks 75

P presented endwise or laterally is not, of course, dependent on the partials of each tone of an instrument being produced by tracks P on one and the same rotor R, but obtains even when the tracks of a rotor are not thus interrelated. 5

Fig. 6 shows two sets of generator devices Q for the one rotor R, with their secondary coils 15 connected to separate tone circuits 27 which are in turn connected to separate branches of the main output circuit 17 that includes amplifier X and sound device S. A variable transformer coupling 290 is interposed in each branch 20 of circuit 17, so that the loudness of the tones from the two sets of devices Q can be varied independently. While the left-hand set of generator devices Q are like those shown in Fig. 1, the right-hand devices Q are different, in that each of them has a plurality of primary exciting coils 20, connected to separate circuits 28, 28, which are also separate from the circuit 28 for the left-hand set. In an instrument with a plurality of sets of playing means or manuals (whether keyboards or playing pedals), the singly-excited set of devices Q may serve one keyboard manual, while the plurally excited set may 25 serve other manuals,—e. g., a second keyboard and a pedal. Generally speaking, I use the word "manual" throughout this specification and my claims in a broad sense, as including tone-control devices of either the hand-played or "keyboard" type or the foot-operated or "pedal" type. The excitation of the several sets of devices Q through the several circuits 28 may be the same or different, as desired by the player 30 from time to time. 35

Vibrato effects

The left-hand set of devices Q are shown in Fig. 6 as mounted on a supporting member or 40 arm 36 extending radially adjacent (above) the rotor R. One end of this member 36 may be (pivotally) supported by the rotor shaft 31, as by means of a collar 360 attached to the member 45 and mounted in an annular groove in the shaft. The other end of the member 36 may be sustained by any suitable support 361 near the edge 50 of the rotor disc R. By oscillating the arm 36 and its set of generator devices Q around the axis of the shaft 31, through a convenient angle and at a suitable frequency, a "vibrato" sound effect is produced at the sound device S—similar 55 to that which a violinist obtains by rocking his finger on a string while bowing it. This is because more crests, plugs, or the like of the tracks 60 P pass the generator devices Q per second when the latter are moving counter to the rotating rotor R, and fewer when the devices Q are moving with the rotor R,—as compared with when the devices Q remain stationary. The arm 36 65 may be oscillated by any suitable mechanical vibrator 363, represented in Fig. 5 by a revolving crank with a pitman connection to the outer end of the arm. The vibrator 363 may be thrown into and out of action as desired by any suitable means (not shown), such as a stop or the like. To simulate the violin vibrato, the arm 36 should 70 make about 8 (complete) vibrations per second, and its maximum angular velocity should be about $\frac{1}{60}$ that of the rotor R. While this vibrato arrangement may be provided for all the rotors R of an instrument, it is generally sufficient to apply it only to the rotors for the higher notes,—say those of two or three of the octaves above middle C. 75

Generator devices with plural coils

Generator devices Q with plural associated generating coils 18, such as that illustrated in Fig. 7, can be used to produce some of the tones of an instrument without corresponding rotors R, by "borrowing" and combining partials from rotors primarily intended for other tones. Like the generator devices Q in Fig. 6, and for the same purpose, the generator device Q in Fig. 7 also has plural exciting coils 20. These are shown on the middle of the core 24, where their effect is greatest.

Organization of an entire instrument

To synthesize a tone of fundamental frequency n and of any desired quality or timbre from the requisite partials n , $2n$, $3n$, $4n$, etc.—including the sub-partial $\frac{1}{2}n$, if desired,—it suffices to combine these partials in the proper proportions of intensity. By varying the number and proportions of the partials employed, any desired tone quality can be produced. While this can be done in other ways, such as hereinbefore indicated, I at present prefer to proportion the partials by regulating the activating currents in the exciting coils 20 of the various generator devices Q. One of many possible ways of doing this is shown in Figs. 8 and 9, which illustrate the electrical features of an instrument adaptable to play organ music, with the full range and variety of tones and effects available on an organ, besides some effects of which ordinary types of organs are not capable. Such an instrument may have any desired number of keyboards or playing manuals (or pedals). Of course the several manuals or keyboards may be operated separately, or coupled together so that playing on one also plays one or more of the others, etc., as is customary in electrical actions of fine organs of ordinary well-known types. I have also devised a very simple way of doing this, which is illustrated in Fig. 9. A large instrument may preferably have both the keyboard or manual range of five octaves from C 65.4 vibrations per second to C 2093 and the pedal octave from C 32.7 up to C 65.4 entirely provided for by full-tone rotors R, making a total of 73 rotors required to provide C notes at both top and bottom of the six-octave range. In a smaller instrument, a pedal octave may be provided by utilizing the $\frac{1}{2}n$ tracks P (and others to afford the desired partials) from one of the manuals M, with corresponding reduction in the number of rotors required.

Borrowing of partials

However, such "borrowing" of tones can readily be carried much further. For instance, a full-tone rotor R for a tone of fundamental frequency n in the lowest octave may be provided with tracks P for frequencies n , $2n$, $3n$, $4n$, $5n$, $6n$, $8n$, $10n$; and similar rotors may be provided for corresponding tones two and four octaves higher, of fundamental frequencies $4n$ and $16n$,—these three rotors being conveniently designated as the n , $4n$, and $16n$ -rotors. Instead, then, of providing a $2n$ -rotor R for the intermediate octave-tone of fundamental frequency $2n$, the first five component partials of this $2n$ -tone may be provided by borrowing from the $2n$, $4n$, $6n$, $8n$, and $10n$ tracks P of the n -rotor, and its remaining three partials by borrowing from the $12n$, $16n$, and $20n$ tracks of the $4n$ -rotor, that produce the third, fourth, and fifth partials of the $4n$ -tone. In like manner, the component partials of the $8n$ -tone may be borrowed from the $4n$ and

16n-rotors; and the necessary partials for the $32n$ -tone can be borrowed from the 16n-rotor, since this tone is of very high pitch, and so does not require so many partials as the lower tones. When partials are thus borrowed, plurally-excited generator devices Q with plural generating coils 18 (such as shown in Fig. 7) are preferably used with the tracks P that are involved, as explained hereinafter in connection with Fig. 9: i. e., each generator device should have as many coils of each type as there are partials to be taken from it. It is interesting to remark that in this way six full octaves can be had in an instrument with only thirty-six rotors R.

Such borrowing of partials may be of course be resorted to for the purpose of reducing the total number of tone-tracks P required in an instrument, without reducing the number of rotors R correspondingly, if at all. For example, eight partials of relative frequencies n , $2n$, $3n$, $4n$, $5n$, $6n$, $7n$, and $8n$ can be provided for all tones (that require so many as eight partials) with 73 rotors having (except the highest rotor) no more than four tracks P apiece, corresponding to frequencies n , $3n$, $5n$, $7n$; or omitting the $7n$ -partial, three tracks P per rotor, corresponding to frequencies n , $3n$, $5n$, will provide for seven partials per tone. Making the corresponding hoops 25 of all rotors R or like diameters and corrugation-pitch throughout the instrument, partials of frequencies n , $3n$, $5n$ may be taken from one rotor R; partials $2n$, $6n$, $10n$ from another revolving twice as fast; partials $4n$, $12n$, $20n$ from another revolving four times as fast; and so on to the rotor R for the top octave,—which, however, may require tone tracks P for $32n$ and $64n$, as well as $96n$ and $160n$,—but will not need tracks for such uselessly high pitches as $192n$ and $256n$.

The borrowing of partials is illustrated in Fig. 9, and is further explained in connection therewith, as well as the use of generator devices Q of the Fig. 7 type.

Borrowing of partials is also practicable when a number of partials are generated from the same track P as described in connection with Fig. 5,—as will readily be understood from the foregoing explanation. In this case, again, plural generating and exciting coils 18, 20 are desirable for each generator-device-limb or member carrying such coils in Fig. 5.

General organization electrically

The illustration in Fig. 8, which shows one rotor R in plan, is limited to two manuals (or pedals) M, M, to avoid confusing multiplication of parts and circuits; and Fig. 9, which affords an edge view of a number of rotors R interconnected as a rotary unit, is limited to the illustration of parts and circuits for one manual M. In Fig. 8, the rotor R is shown with tracks P for three partials only, as for a very high note; and in Fig. 9, only six such rotors (as for corresponding notes of six octaves) are shown. In practice, of course, as many as the full 73 rotors represented in Fig. 10 may be used, with as many partials per rotor as are required to give a good tone in each instance. In Figs. 8 and 9, five stops on each manual are shown, with provision for five different proportional combinations of the three partials illustrated, giving five different tone-qualities for all the notes of each manual. In practice, this might suffice for a small instrument; while on a large one, it might be desired to have up to fifty stops or more to a manual, with provision for a corresponding variety of tone-

qualities in all the notes of each manual. Provision may in like manner be made for any desired variety of tone-qualities in the pedal notes.

The organization of the instrument in Fig. 8 corresponds essentially with that in Fig. 1, with greater elaboration of the component parts to provide for two manuals or keyboards, for multiplicity of partials and variation of tone by variety of proportional syntheses of the partials, and for 10 loud and soft and tremolo effects, etc. There is a sound device S and amplifier X, connected into an output circuit 17 with a branch for each of the manuals M, M; and there is a power circuit 22 with separate branches 22l, 22u for the two 15 manuals. In Fig. 8, a single three-track rotor R is shown in plan, with its generator devices Q; whereas Fig. 9 affords an edge view of six rotors R with their devices Q,—this number sufficing to show the circuit connections entailed by multiplicity of rotors just as well as if a full complement for six octaves were represented. Although a single set of double-excited generator devices Q (such as shown in Fig. 6) could be used with each rotor R, yet to avoid complication of circuits in 20 the drawings, two separate sets of (three) singly-excited devices Q are shown, one set for each of the manuals M, M. In general, the parts and circuits (aside from rotor R, sound device S, and amplifier X) are duplicated for the two manuals 25 M, M in the upper and lower halves of Fig. 8; so that for the most part, only the lower manual M need be referred to in the description.

For the lower manual M, there is a secondary playing or tone circuit 27 to which the secondary leads 16 of the corresponding generator devices Q are connected, as in Fig. 1. There is also a primary playing circuit 28 connected to one side of the lower power circuit branch 22l and to one set of the primary leads 21 of the devices Q, as in 30 Fig. 1. In these primary leads 21 are interposed variable or adjustable calibrating resistances 31, for adjusting and equalizing the exciting currents and the resulting partials; so that each partial of a tone or note may under all circumstances be 35 limited to a desirable maximum loudness. Such resistances 31 are the more useful because the greater linear velocity of the outer tracks P tends to result in greater intensity of the higher frequency electrical impulses and of the overtones 40 produced by them; whereas the lower frequency fundamental produced by an inner track P generally needs to exceed (or at least equal) in intensity the strongest overtone(s) of a note. While this can be compensated by using fewer 45 turns (or finer wire) in the coils 15, 20 for the higher pitches when an instrument is built, the calibrating resistances 31 afford another means of compensation, that is available if it is subsequently desired to change tone quality, or to correct for changes in lead or circuit resistance due 50 to repairs, etc. Still more important, such resistances 31 may be useful in assuring a substantially constant standard of loudness for each tone or note of the keyboard, unaffected by concurrent 55 operation of one, two, three, or more keys K at the same time, as explained hereinafter in connection with the general volume-control circuit V.

In the playing circuits 27 and 28 are the normally open (and self-opening) tone control or 60 playing switches 26, which are closed by the playing key K when it is depressed, as in Fig. 1. When rotor tracks P are at all close together, it may be desirable to make and break both the primary and the secondary playing circuits 27 and 28: the 65 primary in order to prevent faint "cross-partials"

due to slight inductive influence of one rotor track P on devices Q belonging to neighboring tracks, and the secondary to prevent cross-effects due to faint prolongation of a note once sounded, as a result of residual magnetism in the cores of 5 the devices Q which produced such note.

One means of coupling manuals M, M together so that playing of one will play one (or more) of the others is to provide shunting branch or cross playing circuits 27, 28 from the subordinate manual(s) to the dominant manual(s), with corresponding extra switches 26 operable by the various keys K of the dominant manual(s). In Fig. 8, such shunt branches 27, 28 are shown from the upper manual M to the lower manual M, with 15 extra switches 26 for these branches under the lower key K. Make and break switches 38, 38 are shown in these shunt circuits 27, 28, interconnected for operation together by a cam-arm 39 on a shaft N that extends throughout the instrument 20 for actuating corresponding switches 38, 38 in branches 27, 28 of all the upper manual playing circuits. By means such as a stop, tablet, or handle 40 associated with the lower manual M, the shaft N can be operated to couple or uncouple 25 the manuals M, M at will.

The playing circuits 27, 28 for all the rotors R in the instrument are connected to the output circuit 17 and to the power circuit branch 22l through trunk wires or bus-bars H and I (corresponding to the points h, h and i in Fig. 1) that extend throughout the instrument for this purpose, as will readily be understood from comparison of Figs. 8 and 9. As for the primary leads 21 of the devices Q which are not connected to 35 the primary playing circuit 28 as already described, those for corresponding tracks P on all the rotors in the instrument are connected to the same one of three trunk wires or bus-bars J (corresponding to the point j in Fig. 1) that extend 40 throughout the instrument, just like the trunk wires or bus-bars H and I.

Variation of tone quality and of volume

In the connections between the trunk-wires or 45 bus-bars J and the corresponding side of the power circuit branch 22l, means may conveniently be provided for varying the relative strengths of the exciting currents supplied to the several bus-bars, and through them to the primary leads 21 50 of the generator devices Q associated with corresponding tracks P of the various rotors R of the instrument. Thus the relative strengths of the secondary currents generated by these devices Q in coaction with the rotors R will be the same for 55 all the rotors, and the relative intensities of component partials and the resulting tone-qualities will be the same throughout all the notes of the (lower) manual M: i. e., all the notes produced by a given stop of the manual will be diapason, 60 violin, oboe, etc., as in an ordinary fine organ. Provision may also be made in the connection between the bus-bars J and the power circuit branch 22l for varying or modulating the aggregate of the exciting currents supplied to the several bus-bars, thus varying or modulating the 65 loudness of all the notes of the manual alike, to produce a soft or loud effect or a tremolo effect in all, etc.

For the last-mentioned purposes, variable resistance L and T, shown as in series with one another, may be interposed in the connections between power-circuit branch 22l and the several bus-bars J. The resistance L may be adjusted by a loud and soft pedal or stop, etc. (not 75

shown). The tremolo resistance T may be oscillatively varied by any suitable mechanical vibrator t (represented in Figs. 8 and 9 by a crank and pitman), which vibrator may be controlled and started or stopped by a tremolo pedal or stop, etc. (not shown).

For simplicity, the illustration in Fig. 8 includes provision for only four degrees of loudness of each of the three partials produced by the three tracks

- 10 P shown on rotor R, and for five different definite proportional combinations of these partials (for each manual M), under the control of five stops 41, 42, 43, 44, 45, though obviously any desired number of partials, degrees of loudness, proportional combinations, and stops can be provided by adding more parts like those shown. Another stop 46 is also shown, which will be explained hereinafter. Preferably, the stops 41, 42, 43, 44, 45, 46 may be interlocked (as combination 20 pistons of organs often are) to prevent more than one from being operated at the same time. To produce the different strengths of the partials, resistances in the several connections from power circuit branch 22 to the corresponding bus-bars 25 J may be varied, preferably in definite, reproducible steps or gradations. A convenient way is to provide a suitable grouping of resistances for each distinct proportional combination of partials, throwing these groups in and out of circuit 30 by the stops 41, 42, 43, 44, 45. As shown in Fig. 8, a general volume-control circuit V is connected across the power circuit 22, and includes the loudness and tremolo resistances L and T and a partial-proportioning resistance-connection W. 35 all in series with one another. The total resistance of the control circuit V should preferably be low as compared with the total resistances between bus-bars I, J (including parts 28, 26, 21, 37, 28, and 21) for the devices Q pertaining to each rotor R, in order that the activating current in the coils 26 and the loudness of each note may be substantially constant regardless of how many keys K are depressed at any time. The calibrating resistances 37 are helpful in taking care of this. Lines or conductors 38 are connected to the bus-bars J, and lines or conductors 38, 57, 58, 59 are connected to points of the connection W, with suitable amounts of its resistance intervening between them. In the present instance, these amounts are indicated as equal. Corresponding to the stop 41, there is a set of three cross-lines or conductors 51, each connected between a corresponding one of the lines 51 and some one of the lines 56, 57, 58, 59, and including a make and break switch Y; corresponding to the stop 42, there is a similar set of cross-lines 52 with stop switches Y; and so on for the other stops 43, 44, 45, 46. As indicated in Fig. 8, the three switches Y for each set of cross-lines are interconnected, and are operated by the corresponding stop 41, 42, 43, 44, 45, or 46, as the case may be. Operation of each stop 41, 42, 43, 44, 45 brings a different combination of resistances in circuit with the bus-bars J pertaining to the three rotor-tracks P, and so combines the corresponding partials in different relative proportions, giving a tone of different quality.

For example, operation of stop 41 to close its three switches Y gives maximum strength for the partial produced by the inner track P, which may be the fundamental; less strength for that produced by the intermediate track P, say the second partial; and still less strength for the other or third partial. Operation of stop 42 gives 75 a weaker second partial than before, and a third

partial of minimum strength; stop 43 gives second and third partials both of minimum strength; stop 44 gives a fundamental just below maximum, and second and third partials of like and somewhat less strength; stop 45 gives maximum strength of fundamental and third partial, and a second partial somewhat weaker. The tonal qualities of the resulting notes are all quite different.

Elective tone quality

10 While the definite stops 41, 42, 43, 44, 45 are comparable to those of an ordinary organ, Fig. 8 shows the stop 46 as an "elective" stop, with provisions enabling the player to make at will 15 any desired synthesis of partials, in such number and relative strengths as he may choose, thus determining the quality of the tones of the (lower) manual M however he likes. For this purpose, the three cross-lines or conductors 66 controlled by each stop-switch Y operated by the stop 46 may have means for varying the relative strengths of the currents through them. One way of doing this is to provide for each of the three cross-lines 66 (four) branches (661, 25 662, 663 respectively) each connected to one of the lines or conductors 56, 57, 58, 59, with a selector switch y for each cross-line 66 which the player can operate to connect that cross-line to any desired one of its branches. A "dead 30 point" 660 is shown for each switch y, on which it can be placed when it is desired to omit the corresponding partial. To avoid complicating the drawing, Fig. 8 does not show any stop 46, etc., for the upper manual M.

Rotary units and drive

Fig. 9 affords an edge view of six disc rotors R interconnected and driven as one rotary unit U. As here shown, they are not on a single 40 shaft, but grouped in two rotary sections having separate intergeared shafts 31, 31. In using such a sectional unit U to produce the corresponding notes of six octaves, it is advantageous that the section for the notes in the higher octaves should revolve considerably faster than the section for the lower octave notes: e. g., the use of intermeshing toothed gears 67, 68, of ratio 1:8 on the upper and lower shafts 31, 31 makes it easier to adapt such a unit U for generating 50 currents of the widely different frequencies necessary for six notes at octave intervals. As illustrated in Fig. 9, the instrument may if desired have separate output circuits 17 with amplifiers X and sound devices S for the low and high 55 notes, differently adjusted or constructed to produce sounds of widely different pitch with equal correctness. Accordingly, separate bus-bars or trunk-wires H are shown for the rotors R of the two sections of the unit U, connected to the separate output circuits 17 for the low and high notes.

While rotary units U each comprises rotors R for producing corresponding notes of different octaves are generally to be preferred, there is 60 some advantage in constituting the rotary units on a wholly different principle: i. e., so as to include rotors R that produce tones whose fundamentals are of frequencies rather close together,—successive notes in the scale, for instance. When this principle is followed, the adjacent rotors R can be more easily adapted (by differences in number of corrugations or of members in their tracks P) to produce currents of the proper relative frequencies when revolv- 75

ing at the same speed; because the differences of frequency amongst the rotors in one unit U are so much less. In this case, the ratio of the gears 67, 68 may be 1:2 or 1:4, or the like, 5 rather than 1:8; also, the number of rotors R to be included in a unit U is more a matter of arbitrary convenience in design, and may be either more or less than the six shown.

The rotary unit U may be driven from a drive 10 shaft 70 through another (parallel) shaft 71 geared to the (upper) shaft 31 through toothed (bevel) gears 72, 73, and also geared to shaft 70 by toothed bearing. For this purpose, there is shown a coupling gear device or idler 75 meshing 15 with gears 76, 77 on the shafts 70 and 71. The purpose of interconnecting the shafts 70 and 31 in this manner (instead of directly, by intermeshing (bevel) gears on these shafts 70 and 31) will be explained hereinafter, as well 20 as the purpose of two other pairs of gears 76, 77 shown on the shafts 70 and 71. As shown in Fig. 9, shaft 70 may be driven by a constant speed (electric) motor 80, such as a synchronous A. C. motor supplied with current from a lighting 25 or power circuit 81 of 110, 220, or other available voltage. There is also shown an A. C.-D. C. motor-generator set 82 receiving current from the same circuit 81 and supplying direct current 30 of convenient moderate voltage (such as 6 v.) to the power circuit 22 of the instrument.

Aside from those just described, the parts and circuits shown in Fig. 9 correspond generally to those shown in Fig. 8 for the lower manual M, although they are differently arranged; and the 35 stops 43, 44, 45, 46 and their cross-lines, etc., are omitted to avoid crowding and obscurity in the drawings. For the same reason, the circuits for the two lowermost rotors R are omitted, since they would merely duplicate circuits shown. 40 Some modifications of the arrangements illustrated in Fig. 8 are shown in Fig. 9, and will now be explained.

Special tone effects

45 Certain musical tones (e. g., on the piano) are characterized by delayed initiation of one or more partials, so that the quality of the tone changes after it begins to sound. In my instrument, such tones are readily provided for by having separate key-switch(es) 26 for the delayed partials, and arranging to close them in due sequence after the other switches 26. In Fig. 9, this is illustrated in connection with the second rotor R from the top, where the leads 16 of the 50 innermost generator device Q (which may be that for the fundamental n) are not connected to the secondary playing circuit 18 for the other two devices Q, but run directly to an additional, separate switch 26. This extra switch 26 is arranged 55 to be closed by key K simultaneously with the switch 26 of the primary playing circuit 28; but the switch 26 for the secondary playing circuit 27 is arranged to close a little later,—as by placing it at a somewhat lower level, as shown in Fig. 9. As indicative of suitable provision for this, the stationary contacts of the switches 26 that close first are shown as resiliently yielding. Thus the partials from the outermost and intermediate devices Q (e. g., the first and second 60 overtones) begin to sound after the fundamental.

Partial borrowing circuits

Fig. 9 also illustrates the borrowing of partials, as hereinbefore mentioned, so as to enrich the 75 tone of the third rotor R from the top by borrow-

ing from the fourth rotor. As shown, these two rotors R have essentially the same circuits as the top rotor, and all the generator devices Q of the third rotor are also just like those of the top rotor. The two innermost devices Q of the fourth 5 rotor, however, are like those shown in Fig. 7, each having two generating coils 15, and also two exciting coils 20. As shown, the upper coils 15 and 20 of each such device Q are the ones involved in the borrowing. While one side of each 10 of the upper coils 20 for the fourth-rotor devices Q may be connected to the proper busbar J by the same lead-conductor 21 as its companion lower coil 20, the other side of each such upper coil 20 is connected by a separate lead 21 through 15 a calibrating resistance 37 to a part of the primary playing circuit 28 associated with the third rotor R. Similarly, each upper coil 15 of a fourth-rotor generating device Q has its leads 16 connected to an extension of the secondary playing 20 circuit 27 associated with the third rotor R. Thus these two inner fourth-rotor devices Q furnish two additional partials for combination with those furnished by the devices Q of the third rotor itself. Assuming a 2:1 ratio for the gears 25 67, 68, the tracks P of the third rotor R may give frequencies n, 3n, 5n, and the tracks P of the fourth rotor R whence partials are borrowed as just described may give frequencies 2n and 6n. Accordingly, the third-rotor tone will have the 30 five component partials, n, 2n, 3n, 5n, 6n, with an obviously richer quality than its own three tracks P could alone afford.

Mechanical organization of an entire instrument 35

Figs. 10, 11 and 12 illustrate in a diagrammatic way the general organization and one form of mechanism for an entire six octave instrument adapted to be changed over or converted for playing in different scales and keys of musical intonation. The electrical features of Figs. 8 and 9 are omitted, both to avoid confusion and because the mode of conversion illustrated is equally applicable to any type of instrument in which the pitch of the tones depends on speed of rotation,— 45 whether the rotors generate electrical impulses or currents, or control light,—or what-not. However, rotary units and rotors R similar to those of Figs. 8 and 9 are occasionally referred to in the description, for the sake of specific 50 explanation of variant points.

Especially in electrical instruments of the general type hereinbefore described, I prefer to group together and interconnect as one rotary unit U all the rotors R for producing corresponding 55 tones in the several octaves covered by the instrument: e. g., all the C rotors R to form an "octave unit" U, all the "C sharps" to form another such unit, etc. This arrangement not only assures correctly related frequencies for the 60 notes an octave apart under all circumstances, but also obviates all possibility of discords from "cross-induction" between generating devices Q belonging to different rotors R; because all the 65 frequencies that can be generated by cross-induction within such a unit U will be in harmony with one another, as well as with all the frequencies that can be generated by each rotor R and its own devices Q, including all the partials. To prevent the possibility of discords from cross- 70 induction between different units U, they should be magnetically shielded from one another, by spacing them well apart or by other suitable means,—indicated in Fig. 10 by septa 84 (as of soft steel or iron) between some units U. To 75

cover six octaves, Fig. 10 shows twelve octave units U, one (for C) with seven full-tone rotors R, and the rest with six such rotors. However, the number of rotors R required can be reduced by borrowing partials, as already explained. Or by producing the component partials of each note from a single tone-track P as explained in connection with Fig. 5, and providing on one rotor R (such as shown in Fig. 6) a number of tone-tracks P adapted to produce fundamentals an octave apart (n , $2n$, $4n$, $8n$, $16n$, $32n$, and $64n$, if needed), the number of rotors R required can be very greatly reduced: e. g., as an extreme, eleven rotary "units" each consisting of one rotor R with six tracks P each, and one rotary unit consisting of a rotor R with seven tracks P, would suffice for a whole instrument. The units U may all be driven from one main or master shaft 70, preferably through (parallel, axially aligned) intermediate drive shafts 71, one for each unit U, with suitable gearing.

Several types of rotary unit U are illustrated in Fig. 10: e. g., in the unit U at the extreme left, marked as for C tones, a train of seven sections with individual rotor shafts 31 geared together by gears 67, 68 are driven from a shaft 71 through a bevel gear 72 thereon meshing with a bevel gear 73 on one of the shafts 31; the next adjacent unit U, marked as for C sharp D flat, has all its six rotors R on a single shaft 31, driven from a shaft 71 by gears 72, 73; the third unit U, marked as for D, comprises two three-rotor sections with their shafts 31 intergeared by gears 67, 68, and driven from a shaft 71 by gears 72, 73; the fourth unit U, marked as for D sharp E flat, comprises two trains of three rotor sections with individual shafts 31 intergeared by gears 67, 68, and separately driven from one shaft 71 through gears 72, 73; and each of the remaining units U comprises two three-rotor sections with their shafts 31 separately geared to one shaft 71. In the last two types of unit U, the shaft 71 (with gears 72, 73) interconnects two shafts 31 and is thus intrinsically part of the unit, and if desired, the shaft 71 may fairly be regarded as a part of each unit U of the other types.

Changes of scale and key

In order to change the relative speeds of various tone-producing rotary units U and the musical intonation of the instrument, variable-speed driving means are provided, to drive various rotary units at various different speeds for each of such units, whereby the notes of musical scales of the various desired intonations are evoked from the units U, as well as speed-selective and correlating means coacting with the driving means to adjust the relative speeds of the units U to various different concurrent-speed correlations, severally corresponding to different desired musical scale intonations. With a constant-speed motor 80 to operate the units U, variable-speed driving is accomplished by means of interposed gearings which provide a plurality of driving ratios for each of such units U, and the speed-selective and correlating means adjust the several gearings for concurrent operation in various suitable correlations of driving ratios. To adapt the particular mechanism illustrated in Fig. 10 for the purpose of playing in different scales and in different keys, provision is made for several possible driving-gear ratios between the main shaft 70 and the intermediate shaft 71 pertaining to each octave-unit U, in order that each unit U may have a proper rate of rotation for every scale

and every key that is to be available. As one means of providing for this, Fig. 10 shows a group of (three or four) gears 77 on each shaft 71, and corresponding groups of gears 78 on the shaft 70. As a means of bringing various pairs of gears 78, 77 into actual coaction as desired, a coupling-gear device or idler 79 may be provided for each gear-pair 78, 77. This coupler 79 may be rotatably mounted on a shiftable carrier or "coupling arm" 85, which is shown pivoted at 86 about a (fixed) axis parallel with that of gear 75, and with shafts 70 and 71. Preferably, the carrier arm 85 is yieldingly biased to carry coupler 79 (upward) out of mesh with the corresponding gears 78, 77, as by a helical compression spring 87. For convenience, the (three or four) gear pairs 78, 77 (and couplers 79) pertaining to each shaft 71 (and its unit U) may be collectively termed a "driving-gear set" and designated Z. These sets Z may be individually distinguished by the tone-symbol C, C sharp, D, etc., by which each unit U is distinguished in Fig. 10. As one means of throwing into mesh various different couplers 79 in the several gear sets Z, a number of rotatable rods or shafts 88, intended to extend lengthwise of the series of coupling arms 85, are shown in Figs. 11 and 12. In practice, the coupling arms 85 may be over (or under) the corresponding gear-pairs 78, 77, and the rods 88 may overlie (or underlie) the series of coupler arms 85, as indicated in Fig. 11; but to avoid confusion, the coupling arms 85 are omitted from Figs. 10 and 12, and the rods 88 are shown by themselves in Fig. 12. Each rod or shaft 88 is provided with a number of cam lugs or actuator projections 89, one for a coupling arm 85 of every gear set Z: these are shown in Fig. 12 aligned with the corresponding gear pairs 78, 77 of Fig. 10. As shown in Figs. 11 and 12, there are twelve shafts 88, each with twelve actuators 89, and each provided with an operating "stop"-crank or handle 90, conveniently located in reach of the player when seated at the keyboards of the instrument.

To guard against damage to the mechanism if a player attempts to set the instrument in different keys at the same time, any suitable interlocking arrangement may be used. In Fig. 13, this is represented by a longitudinally slidable interlock bar 92 extending under all the crank-handles 90 of the rods 88 (shown in Figs. 11 and 12) and having one single notch 93 which the player can place under any handle, by sliding the bar one way or the other by its own handle 94. On the underside of each crank handle 90 is a projection or lug 95 which ordinarily engages 55 against the top surface of the bar 92 as shown at the left of Fig. 13, thus locking the rod 88 with its actuating arms 89 in the inactive position (shown in Fig. 11 for most of these rods), so that it is impossible to operate the rod 88 to throw in 60 the corresponding coupler 79. But when the notch 93 is brought under a particular crank-handle 90, as shown at the extreme right of Fig. 12, then by pressing down on this handle 90 the player depresses its lug 95 into notch 93 and turns 65 the rod 88 and its actuating arms 89 clockwise to the active position shown at the extreme right of Fig. 11. When he then releases the bar-handle 94 while holding handle 90 down, a long tension spring 96 pulls bar 92 to the right sufficiently to lock a shoulder on lug 95 under a shoulder formed by undercutting one side of notch 93, as shown. By the springs 97 acting on coupling arms 85, the shafts 88 are all biased to 70 turn counterclockwise; so that when the opera- 75

tor subsequently pulls bar 92 a little to the left, they automatically return to inactive position.

In Fig. 13 only two of the shafts 88 and crank handles 90 of Fig. 12 are shown, to avoid confusion.

The number of gear sets Z and rods 88 in Fig. 10 is sufficient for laying in the natural scale in the major keys of C, G, D, A, E, B, F, B flat, E flat, A flat, and D flat, as well as in the equitempered scale; the gear ratios (and tooth-numbers) marked on the various gears 16, 71 in Fig. 10 are adapted for this in an instrument corresponding to the illustrative particulars of design now presently to be set forth; and in Fig. 15 12 each rod 88 is marked with the scale or key into which the instrument will be thrown by operating that rod to throw in the corresponding couplers 75. It is also to be observed that in the light of the following explanation, other 20 gear sets Z (with proper ratios and toothing) and shafts 88 can readily be worked out and substituted or added, so as to permit playing in a great many more keys of the natural scale, or even in scales characterized by very different 25 frequency ratios,—such as the old Greek scale, for example. As Fig. 10 is diagrammatic, no attempt is there made to show the various gears 16, 71, 72, 73, 67, 68 in their true relative diameters. In practice, I now prefer to make all gears 30 76 of each set Z of nearly the same diameter, and likewise all its gears 71; and this is easily done by adopting suitably different gear-tooth pitches. But of course the diameters of coaxing gears 76, 71 must be in the proportions of the 35 numbers marked in Fig. 10.

Illustrative practical gear ratios

For purposes of simple illustration, it is convenient to assume an instrument composed entirely of units U of the type illustrated at the extreme left of Fig. 10; to take such ratios for the gear-pairs 72, 73, and 67, 68, in these units U that the relative rates of rotation of rotors R in each unit are proportional to the numbers 1, 2, 4, 8, 16, 32 which express the frequency relations of tones an octave apart; and to suppose the fundamental tone-tracks P in all rotors R to be made of corrugated wires 25 (such as in Fig. 2) whose corrugations have exactly the same pitch. Taking a fundamental frequency of 440 vibrations per second for the note A, the frequency for middle C below is 261.625 per sec. in the equitempered scale; 264 in the natural scales (keys) of C, F, B flat, and G; and 260.741 in the natural scales (keys) based on E flat, A flat, and D flat. Using 16 corrugations in the wire 25 for the fundamental on the middle C rotor disc R, it follows that this disc must make 16.5 R. P. S.—to employ a convenient abbreviation of “revolutions per second.” With this in view, it is convenient to suppose such a ratio for the gears 72, 73 in this C unit U that the middle C rotor disc R revolves at 1:1 ratio with shaft 71, and to drive the main shaft 70 at a constant speed of 16.5 R. P. S. Throwing into mesh the coupler 75 for the C unit gear pair 76, 71, which is marked (and toothed) 80:80 (Fig. 10) gives

$$70 \quad 16 \times 16.5 \times \frac{80}{80} = 264 \text{ R. P. S.}$$

for the middle C rotor disc R,—the correct frequency for C in the natural scales of C, G, F, and B flat; or throwing into mesh the coupler 75 for the C unit gears marked 80:81 gives

$$16 \times 16.5 \times \frac{80}{81} = 260.741 \text{ R. P. S.}$$

correct for the natural scales of E flat, A flat, and D flat; or throwing in the C unit gears marked 110:111 gives

$$16 \times 16.5 \times \frac{110}{111} = 261.622$$

which is virtually the correct frequency of 261.625 for C in the equitempered scale. Similar calculations will demonstrate the substantial correctness of the other gear ratios (and tooth numbers) shown for the various gear pairs 16, 71 in Fig. 10. While the frequencies thus obtained for the equitempered scale are not mathematically exact (except for A 440, the starting point above), yet the greatest departure for any equitempered scale pitch in the octave of middle C is but 0.052 vibration per second, and the average deviation is only 0.017. As the equitempered scale is in itself only approximately harmonious, these small deviations are unimportant.

For the natural scale, the gear ratios (and tooth numbers) marked in Fig. 10 give mathematically exact frequencies in most cases; but as we get further and further from the middle of the succession of fifths, D flat, A flat, E flat, B flat, F, C, G, D, A, E, B, some of the gear ratios (and tooth numbers) in Fig. 10 give frequencies that are only approximately correct: e. g., the gear ratio 126:118 for C sharp gives a frequency of 281.898, as compared with the correct figure 281.918; and the gear ratio 118:112 for D flat gives a frequency 278.143, as against the correct figure 278.123. However, the deviations from the true pitches are small,—the average deviation being only 0.027 vibration per second,—and are practically inconsequential. The gear ratios indicated in Fig. 10 are here recapitulated: For C,

$$\frac{110}{111}, \frac{80}{80}, \frac{80}{81}$$

for C sharp,

$$\frac{105}{100}, \frac{135}{128}, \frac{118}{112}, \frac{126}{118}$$

for D,

$$\frac{99}{84}, \frac{90}{118}, \frac{90}{81}$$

for D sharp,

$$\frac{99}{84}, \frac{140}{118}, \frac{96}{81}$$

for E,

$$\frac{206}{165}, \frac{81}{64}, \frac{80}{64}$$

for F,

$$\frac{209}{158}, \frac{80}{60}, \frac{133}{101}$$

for F sharp

$$\frac{185}{132}, \frac{90}{64}, \frac{84}{59}, \frac{118}{84}$$

for G,

$$\frac{147}{99}, \frac{81}{54}, \frac{80}{54}$$

for G sharp,

$$\frac{140}{89}, \frac{106}{67}, \frac{128}{81}$$

for A,

$$\frac{150}{90}, \frac{81}{48}, \frac{80}{48}$$

5 for A sharp,

$$\frac{196}{111}, \frac{80}{45}, \frac{194}{109}, \frac{144}{82}$$

for B,

$$\frac{116}{62}, \frac{135}{72}, \frac{112}{59}$$

In these ratios, the upper numbers are suitable for the teeth of the gears 16, and the lower numbers for the teeth of the gears 17.

15 The reason for deviations from exact frequencies in the natural scale is the practical necessity of avoiding the use of gears with the excessively large numbers of teeth corresponding to the large whole numbers that are required to express accurately the ratios of certain natural scale frequencies. With the extremely simple gearing shown in Fig. 10, this compels resort to approximate ratios, realizable by gear pairs 16, 17 with moderate numbers of teeth. However, I have devised several simple means of avoiding appreciable inexactitude in such cases.

More accurate gear ratios: Compound idlers

30 Analysis of natural scale frequency ratios shows that the more complex ones contain the ratio 81:80 or its reciprocal 80:81. For example, the frequency required for C as stated above is 264 in the natural scales of C, G, F, B flat, and E flat, and is 260.741 in the natural scales based on E flat, A flat, and D flat; and

$$\frac{264}{260.741} = \frac{81}{80}$$

40 Again, the frequency for F sharp in the natural scales of G, D, and A is 371.25, and is 375.891 in the natural scales based on E and B; and

$$\frac{371.25}{375.891} = \frac{80}{81}$$

45 One way of introducing the factors 81:80 and 80:81 in the ratios between gears 16 and 17 is to replace the simple coupling idlers 18 in Fig. 10 with coupling gear devices 100 such as shown in Fig. 14 wherever a factor of 81:80 or 80:81 50 can aid in attaining (substantially) exact ratios with practicable numbers of teeth on the coasting gears 16 and 17. As shown in Fig. 14, the coupler 100 consists of a "compound idler" or gear, with provision for shifting it to one side or the other (in the direction of its axis) relative to the gears 16, 17 with which it is intended to coast. Such a side shift of coupler gear 100 can be very easily effected by shifting its carrier arm 85 along its axis or pivot stud 86, as by cam device(s) 101 on the corresponding rod(s) 88, (each) embodying a helical groove 102 in which the arm 85 is always engaged, with a high spot 103 at each end of this groove to take the place of an actuator 89 of Figs. 11 and 12 in depressing the arm 85 when the rod 88 is turned either way. The gears 16, 17 with which the compound gear 100 is to coast are offset out of line, sideways, just a little more than their thickness, as shown in Fig. 14. On the periphery of gear 100 there is a mid-zone or band 105 of 80 teeth wide enough to coast with the offset gears 16, 17 concurrently, and flanked to either side by (narrower) zones or bands 106, 107 of 81 teeth each.

70 Supposing, for purposes of explanation, that 75 the gears 16, 17 shown in Fig. 14 are the 90:64

pair in the F sharp set Z at the middle of Fig. 10, it is apparent that when the mid-zone 105 of gear 100 is thrown into mesh with both of them, as in Figs. 14 and 15, this gear 100 functions as a simple idler (just like the idler 18 for these 5 same gears in Fig. 10), and a frequency.

$$16 \times 16.5 \times \frac{90}{64} = 371.25$$

is obtained for F sharp, which is correct in the 10 natural scales of G, D, and A. In the natural scales based on E and B, however, the proper frequency for F sharp is 375.891, requiring a gear ratio of 729:512. It is impracticable to have gears with so many teeth; but

$$\frac{729}{512} = \frac{90}{64} \times \frac{81}{80}$$

If, then, the gear 100 is shifted to the right from its position in Fig. 14 before being thrown into mesh, so that while its 80-tooth mid-zone 105 still engages the 64-tooth driven gear 17, its 81-tooth zone 106 at the left engages the 90-tooth driving gear 16, then there is obtained a frequency

$$16 \times 16.5 \times \frac{90}{64} \times \frac{81}{80} = 375.891$$

the proper value. It is interesting to observe that the gear ratio shown for this F sharp in Fig. 10 is 84:59, giving a frequency of

$$16 \times 16.5 \times \frac{84}{59} = 375.864$$

an approximation only .027 vibration per second 35 too low. It may also be remarked that if the gear 100 is shifted to the left from its position in Fig. 14 before being thrown into mesh, so that while its 80-tooth mid-zone 105 engages the 90-tooth driving gear 16, its 81-tooth zone 107 at the right engages the 64-tooth driven gear 17, then a frequency

$$16 \times 16.5 \times \frac{90}{64} \times \frac{80}{81} = 366.667$$

is obtained, which while not required for F sharp 45 in any of the natural scale keys marked in Fig. 10, might be necessary for some other scale.

By means of such a compound coupler gear 100, therefore, complex frequency ratios can be resolved into comparatively simple gear ratios, 50 not requiring inordinate numbers of teeth for the gears 16, 17. Furthermore, such a compound coupler is not essentially limited to the ratios 81:80 and 80:81, but can be toothed to afford any other ratios (reasonably close to 1:1) that 55 are desirable in a particular instrument design, such as 111:110 and 110:111, or 203:201 and 201:203, for example.

More accurate gear ratios: Plural drive shafts 60

Another way of resolving complex frequency ratios into simpler gear ratios is to employ a plurality of main driving shafts revolving at suitably different speeds. As shown in Fig. 16, a driving shaft 70 corresponding to that in Figs. 65 10, 11, 12 is supplemented with another (parallel) shaft 110 connected to shaft 70 through suitable gearing, here represented by a chain 111 running around sprockets 112, 113 of suitable ratio and tooth numbers, such as 81:80, that are 70 fast on shafts 70, 110. It is convenient to arrange these shafts 70, 110 at opposite sides of (above and below) the (series of) aligned shaft(s) 71 (corresponding to those in Fig. 10), so that their corresponding gears 16, 76 are at 75

opposite sides of the gears 17 with which they are to coat. A pair of coupling gear devices or idlers 15 is provided for each pair of the gears 16 on the shafts 70, 110: in Fig. 16, they are mounted on opposite arms of a unitary rocking carrier 115, which is pivoted (about at its middle) on a fixed axis 86 parallel with the shafts 70, 71, 110. The carrier 115 is preferably biased to assume the mid-position here shown (in which neither of its idlers 15 is in mesh), as by a spring-pressed guide-rod-head 117 acting on a suitable flat 118 of the carrier 115, located symmetrically opposite its axis 116, so that rocking of the carrier either way compresses the helical spring 119. As shown, one group of the operating rods or shafts 88 (such as in Figs. 11 and 12) are arranged adjacent one arm of the carrier 115, and another group adjacent its other arm; so that the actuator lugs 89 of the two groups of rods throw the opposite couplers 15 into mesh, one coupler to drive gear 17 from the gear 16 on shaft 70, and the other to drive gear 17 from the gear 16 on shaft 110. For clearness, only six of the rods 88 are shown in Fig. 16.

This arrangement affords possibilities of many variations, since corresponding gears 16 on the shafts 70 and 110 may have slightly different numbers of teeth in some cases, besides revolving at slightly different speeds. Moreover, compound couplers 100 such as shown in Fig. 14 may be used with this arrangement, wherever found advantageous.

Flexibility and use of the instrument: The natural scale

The musical advantages of an instrument that can be changed over for playing in different scales and in different keys are very great.

The equitempered scale in general use today is really but a makeshift or compromise, affording the great advantage of playing on one instrument (without retuning) music written in any key, or in a variety of keys, but at the price of important sacrifices of harmony and beauty. Excepting notes just one or more octaves apart, all of the notes in this scale are out of harmony when sounded together, and some very much so. Hence the chords are generally imperfect, somewhat discordant, in fact. This is because the vibration frequencies of such equitempered notes do not bear to one another exactly the simple numerical relations required for perfect harmony.

On the natural scale, as it is termed, these simple numerical relations for perfect harmony exist between all notes intended to sound together; but an instrument with only twelve keys to an octave would not have anywhere near all the notes required for music written in the desired variety of keys. On the contrary, the playing range of any one instrument would be very limited, unless it were built with a great many more keys than twelve per octave. Such an instrument as this, however, would not only be excessively complicated and expensive to build, but far too large and cumbersome to be actually played on. Before the equitempered scale was adopted, two of the black keys of the organ and other keyboard instruments were tuned as F sharp and C sharp, and the other three as D flat, E flat, and A flat, thus providing for scales having up to two sharps or three flats; but it was impracticable to play in any variety of keys.

With my instrument, these limitations are altogether transcended. Playing on it in the

natural scale, all characteristic advantages of that scale are fully realized, including chords that are perfect and beautifully harmonious. An instrument with the simple organization illustrated in Fig. 10 can be set or changed over in a moment for the natural scale in any of the major keys of C, G, D, A, E, B, F, B flat, A flat, and D flat as fundamentals; and without becoming by any means complicated, such an instrument can be built with additional gears and other parts to permit playing in a great many more keys. The scale and key setting or change is made with little more trouble than the setting of an organ stop, or the movement of a handle; the player merely notes the key in which the composition to be played is written (or begins), and operates the proper rod or shaft 88 to set the instrument for the natural scale in that key.

When a musical composition is partly in one key and partly in another, the excursion into another key may be transient: i. e., lasting only a few measures in which are introduced sharps or flats not called for in the "signature" of the key,—"accidentals," as they are called. In many cases, such transient excursions will be met by the instrument without resetting or changing over to another key. An inspection of Fig. 10 shows that 12 pitches are provided in each scale, while only 7 would appear to be needed: the extra five are those required by the adjacent scales in the cycle of fifths, D flat, A flat, E flat, B flat, F, C, G, D, A, E, B. Transitions into other keys are normally up or down in this cycle of fifths; so that the five extra tones are generally adequate; and the accidentals have the correct pitches, unless, of course, the excursion should go too far. If a transition is made from C upward to G, the required F sharp accidental is provided, and in perfect tune. If it is downward from C to F, the required accidental, B flat, is available. However, if the instrument is set for the scale of C, the Re or second note of the scale of G will be found to be too low by the ratio 81/80, and the La or fifth note of the scale of F will be found to be too high by the same interval. In each case, six of the seven notes of the new scale will be in perfect tune, and one of the less important will be off by a small interval. The same holds for any transition from one key to another, up or down, in the series of fifths. If the instrument is set in the key of C, transition up to the scale of D or down to the scale of B flat will involve two notes slightly out of tune. For most compositions, however, the transitions are only to adjacent keys, and are of short duration; so that the slightly faulty pitch of one note of the scale would go unnoticed.

In long compositions, whole sections may be in different keys, as shown by a change of signature; and in such cases, the instrument can be changed over from one natural scale key to another between such sections. Or if a composition involves extensive excursions into far removed and unrelated scales, not provided for by any natural scale setting available in a particular instrument, then the instrument need only be thrown into the commonly used equitempered scale, which was devised for just such purposes. Of course the equitempered scale will commonly be used in playing with other instruments that can only be played in that scale. However, stringed instruments of the violin class can be played in the natural scale; and voices naturally tend to that scale.

Borrowing partials in the natural scale system

For an instrument in which overtones or upper partials are provided by borrowing from tone generators for other notes, my system affords a special advantage: when the instrument is set for the natural scale, its fundamentals are thrown into truly harmonious whole-number frequency-relations with one another, and the borrowed partials for each tone are (mostly) brought into similar relation to the proper fundamentals; whereas on the equitempered scale, this is not the case. On the equitempered scale, for example, for the fundamental frequency of C=261.625 vibrations per sec., the tones available to borrow as overtones and their frequencies are C=523.25, G=783.99, C=1046.50, E=1318.51, and G=1567.98. Being octaves of the lower C, the two C's thus used as second and fourth partials are exact multiples; but whereas the third partial should be $3 \times 261.625 = 784.875$, the borrowed G is 0.88 too low; whereas the fifth partial should be $5 \times 261.625 = 1308.125$, the borrowed E is 10.385 too high; and whereas the sixth partial should be 1569.75, the borrowed G is 1.77 too low. With my system, on the contrary, when the instrument is in the natural scale, the borrowed third, fifth, and sixth partials are in exact harmony, as well as the second and fourth.

I claim as my invention, and desire to secure by Letters Patent of the United States:

1. In a musical instrument, the combination of a plurality of rotary units collectively adapted to produce the desired notes of a plurality of octaves, and each provided with a plurality of gears; a drive shaft with gears for coacting with said gears of said rotary units to drive the units, severally, at a variety of alternative speeds; and selective means for bringing into current coaction various combinations of driving and driven gears such that the notes produced with the several resulting concurrent-speed correlations of the rotary units conform to different musical scales.
2. In a musical instrument, the combination of a plurality of rotary units collectively adapted to produce the desired notes of a plurality of octaves, and each provided with a plurality of gears; a drive shaft with gears for coacting with said gears of said rotary units to drive the units, severally, at a variety of alternative speeds; coupling gear devices for meshing with and operatively interconnecting the pairs of coacting gears of said rotary units and said drive shaft; and selective means for bringing into concurrent mesh as aforesaid various combinations of coupling gear devices such that the notes produced with the several resulting concurrent-speed correlations of the rotary units conform to different musical scales.
3. In a musical instrument, the combination of a plurality of rotary units collectively adapted to produce the desired notes of a plurality of octaves, and each provided with a plurality of gears; drive shafts running at different speeds and having gears for coacting with said gears of said rotary units to drive the units, severally, at a variety of alternative speeds; coupling gears for meshing with and operatively interconnecting the gears of said rotary units and those of said drive shafts; and selective means for bringing into concurrent mesh as aforesaid various combinations of coupling gears such that the notes produced with the several resulting concurrent-speed correlations of the rotary units conform to different musical scales.

4. In a musical instrument, the combination of a plurality of rotary units collectively adapted to produce the desired notes of a plurality of octaves, and each provided with a plurality of gears; a drive shaft with gears for coacting with said gears of said rotary units to drive the units, severally, at a variety of alternative speeds; coupling gear devices for meshing with and operatively interconnecting the pairs of coacting gears of said rotary units and said drive shaft, the gears of some of said coacting pairs being out of line with one another, and the corresponding coupling gear device(s) having portions with the same toothing for meshing with both or either of the gears of such pair and also portions with different toothing for meshing with one or the other of them; means for shifting the last-mentioned gear device(s) axially to bring the diverse portions into positions for variant meshing with the coacting gears that are out of line as aforesaid; and selective means for bringing into current mesh as aforesaid various combinations of the coupling gear devices such that the notes produced with the several resulting concurrent-speed correlations of the rotary units conform to different musical scales.

5. In a system for generating impulses adapted to produce a complex musical tone in a sound device, the combination of generator devices each having primary and secondary windings in a common field; a circuit, with means for connecting it to said secondary windings, and for amplifying the electrical impulses which it receives from them; rotor means for producing in the fields of said generator devices permeability variations at frequencies corresponding to the component partials of the tone to be produced; means for supplying to said generator device primaries exciting currents proportioned to the relative intensities of component partials in the complex tone to be produced; and means for modulating said exciting currents during playing while maintaining their relative values unchanged, so as to produce tremolo effects.

6. In a system for generating electrical impulses of musical frequency and for amplifying and transmitting them to a sound-device, the combination with generator devices each comprising a generating winding, an exciting winding for producing a magnetic field affecting said generating winding, and rotating means for producing permeability variations of musical frequencies in said magnetic fields; of an electric circuit connected to said exciting windings in parallel for energizing them, and having in series therein an adjustable resistance for controlling the current strengths in said exciting windings and the loudness of the sounds evoked by the current from them, and a variable resistance with means for oscillatively varying it so as to produce a tremolo variation of said sounds; and a plurality of parallel branches of different resistances connected in series with each of said exciting windings, with stop-switches in said branches for determining the relative strengths of the exciting currents in the several exciting windings.

7. In a musical instrument of the character described, for generating electrical impulses of musical frequencies and transmitting them, amplified, to a sound device according to the notes to be produced, the combination with playing circuits for connection to the sound device, each including a generating winding, exciting circuits including exciting windings associated with said generating windings, for producing magnetic

fields affecting them, common paramagnetic cores for corresponding generating and exciting windings, and means for producing in said fields permeability variations of frequencies corresponding to the notes to be produced by the instrument; of normally open switches in said playing circuits; normally open switches in said exciting circuits; and a keyboard with playing keys each operative when struck to close the switches 5 in corresponding playing and exciting circuits, whereby cross effects due to cross excitation and residual magnetism are prevented.

8. In a generator for generating electrical impulses of musical frequency for a musical instrument, the combination with a generator device comprising a generating winding and means for producing a magnetic field affecting said winding, and a rotor comprising a paramagnetic ring extending around the axis of rotation of said 10 rotor and travelling in varying proximity to said generator device as the rotor revolves, so as to produce permeability variations in said magnetic field affecting said winding, of a magnetic inductor adjacent the path of travel of said ring, directly opposite said generator device with respect to said axis of rotation of the rotor, for inductively magnetizing the portion of said ring adjacent said generator device to a polarity the reverse of that of the generator device in proximity 15 to the ring, so as to augment the electrical impulses produced in the generating winding as the rotor revolves.

9. In a generator for generating electrical impulses of musical frequency for a musical instrument, the combination with a rotor comprising a serrated soft ferromagnetic ring extending around the axis of rotation of said rotor, of a generator device comprising a generating winding and a paramagnetic horseshoe core therefor, with 20 means for producing a magnetic field affecting said winding, said horseshoe core being mounted

with both its ends closely adjacent the path of travel of said ring as the rotor revolves and spaced apart along said path a distance corresponding to the pitch of the ring serrations, so that when the rotor revolves, the ring completes 5 the magnetic circuit of the core only periodically, as different ring crests concurrently pass the spaced core ends.

10. A musical instrument comprising, in combination, a plurality of rotary tone-producing units; variable-speed driving means in the instrument for driving various rotary units thereof at various different speeds for each of such units, whereby the notes of musical scales of various 10 different intonations are evoked from the units; and speed-selective and correlating means in the instrument coacting with said driving means to 15 adjust the relative speeds of said rotary units to various different concurrent-speed correlations, severally corresponding to different musical scale 20 intonations.

11. A musical instrument as set forth in claim 10 wherein said variable-speed driving means drive the various rotary units at speeds which evoke notes of the equitempered scale intonation, 25 and also at speeds which evoke notes of natural harmonic scales of various different intonations; and said speed-selective and correlating means coact with said driving means to adjust the relative speeds of said rotary units in correspondence 30 to the equitempered scale intonation, and also, alternatively, to various natural harmonic scale intonations.

12. A musical instrument according to claim 10 wherein said driving means comprise, for each of the various rotary units, a gearing providing a plurality of driving ratios; and said speed-selective and correlating means adjust the several 35 gearings for concurrent operation in various correlations of driving ratios.
